SHADE ROLLER

William Dazley, Fairfield, Conn., assignor to
 William F. Smith and Charles F. Schmelz, both
 of Bridgeport, Conn.

Application July 14, 1932. Serial No. 622,425

16 Claims. (Cl. 156—28)

This invention relates to shade rollers, and more particularly to that mechanism or device which affects the operation of such rollers in opposite directions, for raising or lowering the shade, and which, per se, constitutes a complete fixture-unit adapted to be permanently secured to the window-casing and to receive one (left) end of the roller.

The invention has for its principal object the provision of an improved fixture of this character whereby the rotation of the roller in one direction (to lower the shade) may be frictionally resisted; while, when said shade roller is rotated in the opposite direction (to raise the shade), this frictional resistance in the fixture is automatically and materially relieved.

In the drawings, Figure 1 shows a shade roller in its supporting fixtures attached to the inner or opposite faces of a window-casing. Fig. 2 is a side-face view of the roller-operating fixture. Fig. 3 is section on line 3, 3 of Figs. 2 and 4, Fig. 4 is a vertical central section on line 4, 4 of Fig. 3, Figs. 5 to 7 inclusive illustrate a modification, Fig. 5 being a side-face view similar to Fig. 2, Fig. 6 is a section on line 6 of Fig. 7, Fig. 7 is a lateral section on line 7, 7 of Fig. 6. Figs. 8 to 11 inclusive show another modification of the fixture, in fact the preferred form thereof, Fig. 8 being a rear-elevation thereof, Fig. 9 is a front view of the same, Fig. 10 is a vertical cross section thereof, and Fig. 11 is a section on line 11, 11 of Fig. 10.

In brief: the present device is an improved mechanism whereby a shade roller coupled thereto will, firstly, be held frictionally against being rotated by the weight of the down-hanging portion of the shade fabric and its appurtenances, and which will, secondly, relieve this friction when a cord, attached to the pulley or spool of the device, is pulled to rotate the roller in the opposite direction (to raise the shade), and the operator's hand-pull will, therefore, have to overcome only the down-hanging weight of the shade, instead of both: this weight plus the friction mentioned.

Referring to the drawings: the shade roller R consists substantially of a plain cylindrical body to which the upper end of the shade-material S may be secured as usual, by tacks, staples, or otherwise. At its right-hand end this roller is provided with the usual plain trunnion-pin 10, which is adapted to be dropped into the bearing-bracket 11 secured to the casing and has a slot 12 to permit the insertion of the trunnion pin thereinto, or its removal therefrom.

The other or left-hand end of the roller R is provided with a fixed tab-pin 13, whose outer end is preferably rectangular in cross-section to be entered into or removed from a similarly-shaped perforation 14 formed in the face of the 60 pulley-unit whereby the roller is rotatively controlled in either direction, viz: when the shade is being pulled down by hand, or when the pulley is reversely rotated by a cord, to raise the shade.

In its preferred construction, the simplest form, 65 the pulley-unit consists of a pair of similar flanges 15a, 15b, whose hub-portions are press-fitted onto a central cup-shaped shell 15c, having the perforation 14 above referred to. In Fig. 3 it will be noticed that the bottom of the shell 15c 70 projects a short distance beyond the flange-member 15a, so that the pulley-unit may be rotatively supported in a ring-bearing 16 formed on the face plate 17 of a box-like case, indicated in a general way by 18 and having one or more side 75 openings 19 in the annular portion 20 which is provided with attaching-wings 21 for securing the case to the window-casing.

Inasmuch as the diameters of the flanges 15a, 15b are such as to have a loose-running fit on 80 the inner surface of the case-portion 20, the pulley-unit, as a whole, is efficiently supported for rotation in the case without undue friction between the contacting surfaces, the entire organization of case and pulley becoming stabilized by a cover-plate 22 which confines the pulley in the case and is preferably attached to the case-wings 21 in the manner illustrated in Fig. 3, where the wings 21 are draw-punched rearwardly, as at 23, to form a projection adapted to 90 be passed through a perforation 24 in the cover-plate 22, and then to be upset or riveted-over as at 25, thus permanently sealing the case and making the latter a complete unitary device possessing all the essentials of efficiency and rigidity. 95 As the draw-punched projections 23 are, perforce, hollow similar to eyelets, they may be used for the insertion of screws or nails to secure the device to the window-casing, it being understood that the base contours of both, the case and the 100 cover plate, coincide in outline.

As above stated, the pulley or spool is subject to being rotated in one direction, as arrow a, by the shade roller R, when the shade on the latter is being pulled down, during which movement a certain frictional resistance is brought to bear upon the pulley-rotation. In the present instance this resistance or brake-effect is caused by a brake-band 30 circularly formed of spring steel (similar to that of a clock-spring) and so 110

shaped that, when it naturally expands, it fits closely against the inner surface of the hub-shell 15c, the latter, therefore, functioning as a "brake drum" rotatable around the brake-band 30 which has one end bent, as at 31, to serve as a hook or anchor on a slotted projection 32 formed by an inwardly-bent portion of the cover-plate, as is clearly shown in Figs. 3 and 4.

The other end of the brake band is free to come-and-go so that, when the pulley is rotated in the direction of arrow *a*, the free end 31a will be dragged along, causing the brake band to closely contact with the drum-surface, and, therefore causing considerable frictional engagement between the brake band and this inner surface, the strength of such resistance depending upon the temper and size of the band.

On the other hand, when the pulley is rotated in the reverse direction, as arrow *b*, the friction between the brake-band and the drum is automatically relieved and practically nullified, a feature which is desirable when the pulley is thus operated by a cord manipulated by the hand of an operator whose pull need only be sufficient to roll-up the down-hanging portion of the shade.

This cord may be attached to the pulley, even after the entire unit is in position on the window-casing, the flange 15a having a perforation 35 which may be readily brought into register with a "threading-hole" 36 provided in the side-face of the case, and more particularly in the bead of an annular channel 37, so that the end of a length of cord C may be passed through the registered perforations 35, 36 from the outside of the case, the required length of cord be cut off, and the cut-off end knotted, as at 37, to hold that cord-end on the pulley-flange, the beaded channel being provided to afford room for the free revolutions of the knot (with the pulley) and also to guard the same against damage.

The free length of cord passes through one of the side-openings 19 of the case and may be provided at its lower end with a ring or tassel (not shown), as desired.

Attention is called to the fact that, in the organization of the above-described mechanism, the brake-portion thereof is located within the longitudinal space of the pulley-unit, and that, for that reason, the diameter of the brake-drum is comparatively small, as compared with the outside diameter of the pulley-flanges. In some instances of practical use this condition is a matter of necessity, on account of meeting the commercial demand for the "thin model" device to be used as "inside fixture" on the window casing, and practice has fully demonstrated that the efficiency of the present device meets all the required conditions as to thickness, efficiency of service, and adaptability.

Of course, the mechanical organization of the device is equally adapted for the so-called "outside" fixtures, the only change being that of providing the usual "L-foot" on the case, permitting the fixture to be attached to the front face of the window-casing.

When the restrictions regarding the marketable device permit an increase in thickness, the organization of the device may be somewhat modified with, perhaps, even better results as to efficiency, without however changing the principle of operation. Such a modification has been clearly shown in Figs. 5 to 7 incl., in which the case 120 is shown sufficiently "deep" or thick to permit the pulley-cord space and the brake-band space to be placed side by side. (See Fig. 6.)

In this instance the pulley-flange 15b and hub-shell 15c may remain the same as those described above; while the pulley-flange 15a is now replaced by another (150a) having an annular flange 151 which externally is in running contact or support with the interior of the case 120 and therefore stabilizes the position of the pulley within the case, offering, as it does, a substantial bearing surface between the two parts.

On the other hand, the central bearing of the first device, viz: the hub-shell 15c provided in the case-flange 16 is still maintained in the present instance, only in modified form, the shell 15c being supported rotatively on the outside face of a hub 123 formed on the cover-plate 122 and affording a long and substantial bearing for the parts.

Now, when the brake-band is to be considered, we find that, owing to the large inside diameter of the pulley-flange 151, the "curl" of the band 130 is also considerably larger than that of the brake-band 30, so that the self-conforming tendency of the band 130 is very much enhanced, and smoother action in either direction of rotation will naturally result, the band 130 requiring also less width than the band 30 and yet having greater frictional resistance.

While in the other construction, the brake-band 30 was anchored with one end on the projection 32 formed on the cover plate, the present construction anchors the brake-band on the projection 132 lanced in the face-plate 170 of the case 120. In either case, the brake-band is anchored on the case-portion of the device, directly or indirectly; while it frictionally engages the pulley-unit, either by contact with one of the flanges, or with the hub-shell.

While there is no reason why the ring-flange bearing of the first construction should not be maintained in the second construction, the hub-bearing 123 of the latter appears more mechanically efficient, and, therefore, the side face 170 of the case may be cut away entirely to clear the path of the knot 37 which thus remains in plain sight at all times.

Furthermore, in view of the fact that the case openings 19 are provided in duplicate, the pulley-cord may be led to rotate the pulley either in one direction or in the other, depending upon the hang of the shade on the roller and the right-or-left position of the brake-band whose reversibility in its anchorage is obvious.

Upon due reflection, it will be found that altho the two constructions described are modifications of each other only, without in any way altering the essential features or the principle of operation, yet both forms are susceptible of being combined in the same device, in which case the second construction of the case, viz: 120, would be the one used, the pulley-unit would also be of that type, 151, but having two frictional brake-band resistances, viz: the rim-flange band 130, as well as the hub-shell band 30, the latter being anchored on the cover plate 22 which now would replace that shown in Fig. 6. Such combination of brake-bands works out very advantageously in cases where abnormally-long shades are to be used and considerable weight has to be compensated for.

In Figs. 8 to 11 inclusive, I have illustrated another modification which may be considered as the most desirable type because it combines the best mechanical elements of both of the other two constructions, and also permits a combination of both, the hub-brake of construction No. 1

with the rim-brake of construction No. 2, all in the same device, the organization now being such that, according to requirements, either the hub-brake or the rim-brake may be used independently of each other, or both may be used at the same time; therefore making this device adapted for three different resistances, viz: light, medium and strong, without in any way changing any of the parts except the brake-bands.

10 In this instance, the hub-shell 15c of the pulley is journaled at one end in the case-flange 16 (as in No. 1), while at its other end it is journaled on a hub 223 similar to but shorter than the hub 123 of No. 2 (see Fig. 6), the hub 223 being formed 15 by cupping the cover plate 222, so that a portion of the cup-bottom may be lanced and bent outward to form the anchorage 233 for the hub-brake band 230, the latter being in frictional contact with the interior surface of the pulley-hub-shell, as before.

From the above, it will be understood that in this (No. 3) construction the pulley-shell 230 is journaled at both ends, viz: at its outer end within the ring bearing 16, of the case 220, and at its 25 other end on the outside of the plate-hub 223. Now, as both (the case and cover plate) are in axial alinement, it follows that the pulley is well journaled in its position, and it is essentially immaterial whether or not the pulley-flanges have 30 any peripheral bearing-contact with the interior of the case 220 or not.

Substantially as in No. 2, (Fig. 6), the outer pulley-flange has the outwardly-extending annular flange 251 whose inner surface is frictionally engaged by the brake-band 330 which, in the present instance shown, consists of a spring-wire, one end (331) of which is bent at right angle to the plane of the wire-curl, and entered into a 35 perforation 332 in the front plate of the case and thus becomes anchored at that point.

Inasmuch as the case-plate 270 has the ring-bearing 16, this plate cannot now be entirely cut out as is the plate 170 of No. 2, so that the cord-knot 37 will now travel with the pulley in the 45 confined space formed between the side and annular flange of the outer pulley-flange and the inner face of the case-plate, a threading hole 36 being provided in the case-plate, as in No. 1.

In recapitulation of the above, it may be emphasized: that this No. 3 construction constitutes the most desirable form of the device because it possesses a certain "flexibility" as to distribution or variation in frictional resistance which cannot be attained in either of the other two (Nos. 1 and 2) constructions. In other words: With the same component parts (case, pulley, cover-plate) of the No. 3 device, and two 55 brake-bands (for hub and rim of the pulley respectively) I am enabled to obtain three different brake-resistances, viz: 1, for light duty, by employing the hub-brake band only, for small and light-weight shades. 2, for medium duty, adapted for medium sizes and weights of shades, by using the rim brake-band only; and 3, for extra 60 large sizes and weights of shades, by using both 65 brake-bands simultaneously.

Analytically, the preferred form of the device comprises one case, one pulley-unit, two brake-bands, and cover-plate, a total of four parts (besides a length of raising-cord), which may be 70 easily and quickly assembled into one permanent fixture possessing simplicity, stability, strength and efficiency in question.

The assembling may best be performed as 75 follows:

1. Place the large brake-band into its place within the pulley-flange, the anchoring-end projecting outward therefrom.

2. Place the pulley-unit into the case, the anchoring-end of the brake-band entering the 80 perforation in the case-plate.

3. Place the small brake-band into the hub-shell of the pulley.

4. Place the slot of the anchor-tab of the cover plate over and engaging the anchor end of the 85 small brake band and bring the eyelet-projections of the case-wings into register with and through the perforations in the wings of the cover-plate, and

5. Head or rivet these projections to permanently unite these parts, thus forming the complete fixture.

By turning the pulley within the case sufficiently to bring the cord-perforation of the pulley-flange and the threading-hole in the case plate into register, the cord may be threaded from the outside of the case and the threaded-in end is then pulled-through until the cord-knot stops it, whereupon the cord may be cut to proper length and a tassel or similar hand-hold may be 100 attached to the cord-end to keep the cord taut and possibly assist in counterbalancing the shade-weight.

It should, of course, be understood that, as far as the present invention is concerned, the position of the pulley in the case may be reversed, end-for-end, in which instance the large or rim-brake band will naturally be anchored on the 105 plate 222, instead of on the side face plate 270.

Other changes may be made in the particular 110 construction as well as in the general organization of the several component parts of the device, especially in the reversal in location of the latter, without departing from the spirit of the invention.

I claim:

1. A device of the character described comprising a case, a pulley adapted to have one end of the shade roller coupled thereto, a brake-band anchored at one end on said case and having its 115 free portion frictionally engaging said pulley, and a plate secured to said case and retaining said pulley within the same.

2. A device of the character described comprising a case, having in its side-face a ring-bearing, 120 a pulley having a hub journaled at one end in said ring-bearing and comprising a pair of spaced flanges, one of said flanges having a laterally projecting annular flange, and a brake-band anchored at one end on said case and having its free 125 portion frictionally engaging the inner surface of said annular flange.

3. A device of the character described comprising a support-case having in its side-face a ring-bearing, a pulley having a hub journaled at one 130 end therein, a cover-plate having a hub cooperative with said case-bearing for rotatably supporting said pulley in the case, and a brake-band anchored at one end on one of said support-members and having its free portion frictionally 135 engaging said pulley.

4. A device of the character described comprising a case having in its side face a ring-bearing, a pulley having a hub journaled at one end therein, a cover-plate having a hub, cooperative with 140 said case-hub for rotatably supporting said pulley in the case-bearing, and a pair of brake-bands, each being anchored at one of its ends, and each having its free end frictionally engaging said pulley for resisting its rotation in one direction.

5. A device of the character described comprising a case having in its side-face a ring-bearing, a pulley comprising a pair of spaced flanges and a hub-shell journaled at one end in 5 said bearing, a cover-plate secured to said case for retaining said pulley within the same, and having a portion projecting into said shell for anchoring one end of a brake-band thereon. 80
6. A device of the character described comprising a box-like case, a pulley rotatably supported in said case and comprising a pair of spaced flanges to form a cord-space, said case having in its side-face an annular beaded channel having a threading-hole for the pulley-cord, 10 and a brake-band anchored at one end on said case and having its free end frictionally engaging said pulley to resist the rotation thereof in one direction. 85
7. A device of the character described comprising a box-like case, a pulley rotatably supported 20 therein and comprising a pair of spaced flanges to form a cord-space and a hub-shell, and a cover-plate secured to said case for retaining said pulley within the same, and a brake-band anchored at 25 one end on said cover-plate and having its free end frictionally engaging the inner surface of said hub-shell. 90
8. A device of the character described comprising a box-like case, a pulley rotatably supported 30 therein and comprising a hub-shell and a pair of spaced flanges, one of said flanges having a laterally-projecting annular flange, a cover-plate for rotatably supporting said pulley and secured to said case, and a brake-band anchored at one 35 end on said case and having its free portion frictionally engaging the inner surface of the hub-shell. 95
9. A device of the character described comprising a box-like case, a pulley rotatably supported 40 therein and comprising a pair of spaced flanges, one of said flanges having a laterally projecting annular flange, and a hub-shell adapted to have one end of the shade roller coupled thereto; a cover-plate secured to said case and retaining 45 said pulley within the same; and a brake-band anchored at one end to said cover-plate and having its free portion frictionally engaging said hub-shell for resisting the rotation of said pulley in one direction. 100
10. A device of the character described comprising a box-like case, a pulley rotatably supported 50 therein and comprising a pair of spaced flanges, one of said flanges having a laterally projecting annular flange, and a hub-shell adapted to have one end of the shade roller coupled thereto; a cover-plate secured to said case and retaining said pulley within the same; a brake-band anchored at one end to said cover-plate and having its free portion frictionally engaging said hub-shell, and another brake-band anchored at one end 55 on said case and having its free portion frictionally engaging said annular flange, both brake-bands cooperating in resisting the rotation of said pulley in one direction. 105
11. A device of the character described comprising a stationary member, a pulley having a hub adapted to have one end of the shade roller coupled thereto and comprising a pair of spaced flanges to form a cord-space, one of said flanges having a laterally-projecting annular flange; and a pair of brake-bands, each being anchored at one of its ends, and each having its free end frictionally engaging said pulley for resisting its rotation in one direction. 110
12. A device of the character described comprising a stationary member; a pulley adapted to have one end of a shade roller coupled thereto and comprising a pair of spaced flanges, one of said flanges having a laterally-projecting annular flange; and a brake-band anchored at one end on said stationary member and having its free portion frictionally engaging said annular flange, for resisting its rotation in one direction. 115
13. A device of the character described comprising a box-like case; a pulley rotatably supported within and on said case and comprising a pair of spaced flanges to form a cord-space and adapted to have one end of a shade roller coupled thereto; a brake-band anchored at one end on the side-face of said case and having its free portion frictionally engaging said pulley, and a cord secured at one end to one of the pulley-flanges for rotating said pulley in the brake-relieving direction. 120
14. A device of the character described comprising a box-like case, a pulley rotatably supported within and on said case and comprising a pair of spaced flanges to form a cord-space and adapted to have one end of a shade-roller coupled thereto; a brake-band anchored at one end on the side-face of said case and having its free portion frictionally engaging said pulley; and a cord secured at one end to one of the pulley flanges for rotating said pulley in the brake-relieving direction, said pulley being rotatable against the frictional resistance of said brake-band by a "down-pull" on the shade. 125
15. A device of the character described comprising a box-like case open at one side; a pulley adapted to have one end of the shade-roller coupled thereto and rotatably supported in said case; a brake-band anchored at one end and having its free end frictionally engaging said pulley; and means on the case projecting over the uncovered side-face of the pulley for retaining the latter within said case. 130
16. A device of the character described comprising a box-like case open at one side; a pulley adapted to have one end of the shade-roller coupled thereto and rotatably supported in said case; a brake-band anchored at one end and having its free end frictionally engaging said pulley; and means on said open case-side for closing the open side of said case to retain said pulley against lateral displacement within the same. 135

WILLIAM DAZLEY.
